United States Patent Office

Des. 191,406
Patented Sept. 26, 1961

191,406

TEETHING SPOON

Nancy A. Newmark, San Diego, Calif., assignor to Progressive Products, Inc., La Mesa, Calif., a corporation of California

Filed Sept. 14, 1960, Ser. No. 62,133

Term of patent 14 years

(Cl. D44—29)

FIG. 1

FIG. 3

FIG. 2

FIG. 4

In the drawings:

FIGURE 1 is a perspective view of a teething spoon showing my design.

FIGURE 2 is a top plan view of the spoon.

FIGURE 3 is a front view of the spoon; and

FIGURE 4 is a side elevational view thereof.

I claim:

The ornamental design for a teething spoon, substantially as shown.
